ALEXANDER VOSMAER, OF WATERGRAAFSMEER, AND ADRIAAN LEBRET, OF Utrecht, NETHERLANDS, ASSIGNORS TO OZON MAATSCHAPPI SYSTEEM A. VOSMAER, OF AMSTERDAM, NETHERLANDS.

APPARATUS FOR TREATING LIQUIDS WITH GASES OR GASES WITH LIQUIDS.

SPECIFICATION forming part of Letters Patent No. 709,379, dated September 16, 1902.

Application filed April 2, 1902. Serial No. 101,036. (No model.)

To all whom it may concern:

Be it known that we, ALEXANDER VOSMAER, engineer, residing at Watergraafsmeer, and ADRIAAN LEBRET, engineer, residing at 5 Utrecht, in the Kingdom of the Netherlands, subjects of the Queen of the Netherlands, have invented certain new and useful Improvements in Apparatus for Treating Liquids with Gases or Gases with Liquids, of 10 which the following is a specification.

The present invention relates to that class of apparatus in which any kind of a liquid has to be put into contact with a gas—such, for instance, as apparatus for treating water 15 by means of ozone, gas-purifiers, and generally all apparatus in which the gas and liquid to be put into contact with each other preferably circulate in opposite directions. An essential and important condition is to assure 20 in this kind of apparatus the passage of the gas through the liquid in as fine a state of division as possible in order to produce as complete a contact as possible between the gas and liquid and to simultaneously prevent 25 the gaseous bubbles from being carried with the liquid moving in the opposite direction. It is particularly difficult to simultaneously fulfil these two conditions, since the division of the gaseous current into comparatively 30 small particles or bubbles can only be effected in the liquid itself by opposing to the said current a comparatively great resistance, the result of which is to cause the gas to follow the way offering the least resistance—that is to 35 say, that of the outlet-opening through which the liquid (in the ordinary way flowing in the opposite direction to the gas) passes out. Thus it appears that the desired results can only be obtained at the expense of each other, the 40 means hitherto used for producing the division of the gaseous current into bubbles causing the gas to be carried away by the liquid and rendering even those measures ineffective which might have been taken in order to 45 prevent this inconvenience.

The object of the present invention is to overcome these difficulties and to provide an

apparatus in which the gas can be divided into exceedingly small bubbles without the said bubbles being carried away by the liquid escaping from the apparatus. 50

With a view to obtaining this object the invention essentially consists in operating the division of the gaseous current at the moment it passes into the liquid in such a 55 manner that the gaseous bubbles can freely rise to meet the liquid current without meeting with any particularly great resistance, while, on the other hand, a greater resistance is opposed to the carrying away of the gaseous 60 bubbles toward the outflow-opening of the liquid.

In the practical realization of the present invention the division of the gaseous current at the moment it passes into the liquid is obtained by means of a plate provided with extremely small perforations, forming the bottom of the apparatus and leaving passage for the gas under pressure without, however, providing passage for any liquid, (by reason of 65 the fineness of said perforations,) while the gaseous bubbles are prevented from being carried away by the liquid current by means of a perforated screen allowing of the liquid passing out, but constituting for the gaseous 70 bubbles an obstacle sufficient to cause them to preferably pass toward the natural outlet-opening of the gas after having freely passed 75 through the current of liquid.

In the annexed drawing we have shown in 80 vertical section an apparatus constructed according to our invention.

The apparatus is composed of a receptacle or cylinder *a* of suitable height, in which the water or other liquid to be treated circulates, 85 said water or liquid being admitted into the upper part through a pipe *b*. The said receptacle *a* rests upon a part *c*, to which the outlet-pipe *d* for the treated liquid is attached. This part *c* bears on a tubular or cylindrical 90 part *e*, in which the pipe *f* for supplying the gas to be put into contact with the liquid opens. Between the two parts *c* and *e* is arranged a bottom *g*, provided with perforations

h of a sufficiently small diameter—for instance, capable of being reduced to one-twentieth of a millimeter—to prevent the liquid from flowing from the upper part into the lower part of the apparatus. The said perforations are provided in the central part of the bottom *g* under a part or tube *i*, projecting upward for a short distance into the upper part *a* of the apparatus. Between the tubular projection *i* and the wall *c* is arranged an annular screen *k*, provided on its vertical wall with perforations *l*, through which the liquid must pass in order to reach the annular chamber *m*, with which the outlet-pipe *d* 15 communicates. These perforations have consequently a comparatively greater diameter—for instance, about one-fourth of a millimeter—than those of the bottom *g* in order not to oppose a too great resistance to the passage of the liquid. It is easy to understand from the operation of the apparatus that the conditions specified above are thus fulfilled—that is to say, that the gas passes freely in a fine state of division through the liquid current without being carried away by the latter toward the outlet-opening of the liquid. Indeed the gas under pressure supplied to the apparatus through pipe *f* and filling the part *e* is divided into exceedingly small bubbles 20 at the exact moment it passes into the liquid resting on bottom *g* without being allowed to flow through the small perforations provided in said bottom. The said bubbles, obtained at the expense of only an excess of pressure given to the gas, are conducted by the tubular projection *i* and without meeting any particular resistance above the perforations *l* of the screw *k*, through which the liquid must 25 pass in order to reach the outlet-pipe *d*. The said bubbles consequently rise freely into the upper part of the apparatus, leaving it, for instance, through an outlet or aperture *n*. On the contrary, by aid of the screen *k* a certain resistance, which is greater than that 30 which is opposed to the bubbles flowing directly to the outlet *n*, is opposed to the gas-bubbles, which might be carried away by the liquid current. As a consequence the said bubbles preferably follow the way opposing 35 the lowest resistance, and thus rise into the upper part of the apparatus after having been retained by aid of the screen *k* in such a manner that the liquid passing through the perforations of the screen to the outlet-pipe *d* is as free as possible from gaseous bubbles. 40

It will be observed that nothing would be changed in the operation of the apparatus if the perforated bottom *g* would be placed at the upper end of the cylinder part *i* or if the parts *a c e* would form only a single receptacle. 45

Having thus described our invention, what we claim is—

1. In an apparatus of the character described, the combination of a first receptacle

fitted with a liquid-inlet pipe, a liquid-outlet pipe and a separate gas-outlet, a part or second receptacle fitted with a gas-inlet and upon which rests the first receptacle, means for dividing in very small bubbles a gaseous current passing from the second receptacle into the first receptacle, the said means being located between the two receptacles and means for opposing a resistance in the first receptacle to the passage of the gas-bubbles through the liquid-outlet pipe, substantially as and for the purpose described. 70

2. In an apparatus of the character described, the combination of a receptacle fitted with liquid inlet and outlet pipes, a gas-inlet pipe and a gas-outlet, a perforated diaphragm placed in the said receptacle between the gas and liquid inlet pipes, the perforations of said diaphragm being of a sufficiently small diameter to prevent the liquid from flowing through said perforations, but allowing the passage of a current of gas under pressure and a resistance placed before the liquid-outlet pipe and preventing the passage of gaseous bubbles through said pipe, substantially 80 as and for the purpose described.

3. In an apparatus of the character described, the combination of a receptacle fitted at its upper part with a liquid-inlet pipe and a gas-outlet and at its lower part with a gas-inlet pipe, a perforated diaphragm placed in said receptacle between the liquid and gas inlet pipes and adapted to prevent the flowing of the liquid through said diaphragm, a liquid-outlet pipe placed near said perforated diaphragm and a perforated screen placed before said liquid-outlet pipe, substantially 90 as described and for the purpose set forth. 95

4. In an apparatus of the character described, the combination of a receptacle fitted at its upper part with a liquid-inlet pipe and a gas-outlet and at its lower part with a gas-inlet pipe, a perforated diaphragm placed in said receptacle between the liquid and gas inlet pipes and adapted to prevent the flowing of the liquid through said diaphragm, a liquid-outlet pipe placed near said diaphragm, a perforated screen placed before said liquid-outlet pipe and a tubular projection extending from the perforated diaphragm to above 105 the screen of the liquid-outlet pipe, substantially as described and for the purpose set forth. 110

5. In an apparatus of the character described, the combination of a receptacle fitted at its upper part with a liquid-inlet pipe and a gas-outlet and at its lower part with a gas-inlet pipe, a perforated diaphragm placed in said receptacle between the liquid and gas inlet pipes and fitted with very small perforations adapted to prevent the flowing of the liquid through said diaphragm, a liquid-outlet pipe placed near said perforated diaphragm, a perforated screen forming an annular chamber in which opens said liquid- 120 125 130

outlet pipe, the perforations of the said screen being of greater diameter than the perforations of the perforated diaphragm and a tubular projection extending from the perforated diaphragm to above the screen, substantially as described and for the purpose set forth.

In witness whereof we have hereunto set our hands in presence of two witnesses.

ALEXANDER VOSMAER.
